RECOIL-OPERATED FEEDING APPARATUS
FOR A COMBUSTION CHAMBER USED IN
AERIAL PROPULSION

Robert H. Goddard, deceased, late of Annapolis, Md., by Esther C. Goddard, executrix, Paxton, Mass., assignor of one-half to The Daniel and Florence Guggenheim Foundation, New York, N. Y., a corporation of New York

Application September 5, 1946, Serial No. 694,922

1 Claim. (Cl. 60—35.6)

1 This invention relates to combustion chambers of the type having open discharge nozzles and adapted for use in rockets and rocket craft. The invention relates more specifically to the provision of improved feeding apparatus for such combustion chambers, which feeding apparatus is operated by the recoil of the chamber as successive charges of the combustion mixture are ignited therein. Improved automatic valves are also provided, together with means for cooling the valves and the combustion chamber walls.

The invention further relates to arrangements and combinations of parts which will be hereinafter described and more particularly pointed out in the appended claim.

Preferred forms of the invention are shown in the drawings, in which

Fig. 1 is a general plan view showing a combustion chamber associated with a preferred form of the invention, and with certain details omitted for clearness;

Fig. 2 is an enlarged plan view of the improved feeding apparatus, partly in section, and showing certain additional details omitted in the general view of Fig. 1;

Fig. 3 is a further enlarged sectional plan view of one of the automatic valves;

Fig. 4 is a sectional plan view of a modified valve construction;

Fig. 5 is an end view of certain parts, looking in the direction of the arrow 5 in Fig. 4; and

Fig. 6 is a side elevation of a liquid-cooled valve.

Referring of Figs. 1 and 2, a combustion chamber C and discharge nozzle N are shown mounted to slide in a fixed supporting frame 10. Pumps 12, 14 and 16 are provided to deliver liquids to the combustion chamber C, the pump 12 delivering liquid oxygen through a feed pipe 20 (Fig. 2) to a jacket space 21 associated with the combustion chamber head 22.

The pump 14 delivers liquid fuel, as gasoline, through a feed pipe 24 to an annular jacket space 25 in the combustion chamber head 22. These liquids are sprayed from the jacket spaces 21 and 25 through spray openings 27 and 28, and the sprays of the two liquids intersect and are intermingled as indicated by the arrows in Fig. 2.

The pump 16 is connected by a feed pipe 30 to an annular passage or volute 31, and is provided to supply water or an inert liquid which enters the combustion chamber C tangentially through feed openings 32 and which cools the thin wall of the combustion chamber. Additional annular passages or volutes 34 and 35 may

be connected to the feed pipe 30 for more complete cooling of the chamber wall.

The three liquids may be supplied under pressure from tanks T, T' and T2. The construction of one of the pumps, as 12, is shown in detail in Fig. 3, and comprises a casing or cylinder 40 mounted on a cross arm 41, which in turn is supported on the fixed frame 10 (Fig. 2). Liquid oxygen is fed to the cylinder 40 through a supply pipe 42.

A piston 45 is slidable in the cylinder 40, and leakage between these parts is prevented by a bellows packing 46. The piston 45 is mounted on a cross brace 50 carried by a movable frame 51 (Fig. 2) which is mounted on and slidable with the combustion chamber C at each recoil of the chamber.

The longitudinal position of the chamber C and frame 51 is controlled by springs 55 and 56 (Fig. 2) which yieldingly resist displacement of the chamber and frame in either direction from normal mid-position. Threaded studs 59 and 58 may be used to increase or decrease the pressure of either spring.

Each pump is provided with a check valve V (Fig. 3) between the supply pipe, as 42, and the cylinder 40 and with a second check valve V' between the cylinder 40 and the feed pipe, as 20, which connects the pump to the associated jacket space or volute.

Each check valve comprises a streamlined member 60 or 60a slidable in a perforated guide ring 64 and engaging a narrow seating surface 65. A spring 66 normally seats the valve member 60, and a spring 67 seats the valve 60a. The spring 66 is relatively light, and the spring 67 is just strong enough to resist the tank or supply pressure, say thirty pounds, and to thus prevent flow from the cylinder 40 to the feed pipe, as 20, when no recoil is taking place.

With this construction, at each movement of the piston 45 to the right or in the direction of the arrow a in Fig. 3, the check valve V will open and the cylinder 40 will be filled with liquid. On return from the recoil, the piston 45 will be forced into the fixed cylinder 40. The check valve V will immediately close, preventing return of the liquid to the supply pipe 42, and the check valve V' will open to deliver the liquid in the cylinder 40 to the feed pipe 20.

Consequently, a measured quantity of liquid will be delivered to the combustion chamber after each explosion therein, and the amount delivered will naturally be proportionate to the cylinder capacity of each pump. By correctly proportion-

ing the pumps, the fuel, oxidizing liquid and cooling liquid will be fed in the desired proportions to the chamber C.

Ignition in the chamber C may be under the control of a spark-plug 70 (Fig. 2) wired to a source of current, as a battery B, and including normally spaced contact members 71 and 72, mounted on the fixed frame 10. The spark-plug 70 and the contact 72 are grounded and the contact 71 is insulated. A screw 73 adjustably mounted on the sliding frame 51 closes the circuit by engaging and moving the contact 71. Ignition takes place as the cylinder reaches forward position after each recoil movement.

The bellows packing 46 substantially prevents leakage between the cylinder 40 and piston 45 during the recoil movements. Any slight leakage which may occur is returned to the supply pipe 42 through an expansible drain connection 75.

If it is desired to increase the area of the check valve openings to permit more rapid flow, the valve construction shown in Figs. 4 and 5 may be utilized. In this case, the fixed cylinder 80 is provided with a disc 81 having a plurality of port openings 82, and the movable valve member comprises a movable spider 83 having port-covering portions 84. The spider 83 is mounted on a non-rotatable guide-rod 85 and is seated by a light spring 86. The piston 90 has a similar perforated end disc 91 and a spider 92 with port-closing portions 93 which are seated by a light spring 94.

The operation is the same as previously described but, at each recoil movement, a plurality of port openings are uncovered, instead of the single opening found in the construction shown in Fig. 3.

For starting purposes, a hand lever 100 may be connected to the frame 51 by a link 101. This lever may be moved in the direction of the arrow b to charge the pump cylinders. Release of the handle allows the frame to return to normal position and with the usual pumping action.

Flow to the pump cylinders is preferably controlled by valves 110, 111 and 112 (Fig. 2) which may be connected to a single operating rod 114, by the use of which simultaneous supply of all three liquids to the pumps may be effected.

Where one of the pumps, as the pump 120 (Fig. 6), is used to pump a very cold liquid, such as liquid oxygen, it may be desirable that this pump should be precooled. This may be accomplished by providing a coil 121 surrounding the pump cylinder and connected to the liquid oxy-

gen storage tank, one end of the coil being connected to the bottom of the tank and the other to the top. Circulation through the coil will then precool the pump cylinder.

The rate of feed may be controlled by varying the stroke of the sliding frame, as by an adjustable stop screw 130 (Fig. 1). The extent of opening of the valves 110, 111 and 112 (Fig. 2) may also be adjusted by a screw 131.

Having thus described the invention and the advantages thereof, it is not desired that the invention be limited to the details herein disclosed, otherwise than as set forth in the claim, but what is claimed is:

In a rocket apparatus, a fixed frame, a combustion unit slidable by recoil in said fixed frame on the firing of each successive charge of a liquid combustion mixture and said unit comprising a combustion chamber and a discharge nozzle permanently secured thereto, separate pumps for the liquid fuel and for the liquid oxidizer in said combustion mixture and each pump comprising a cylinder and piston, one part of each pump being secured to said fixed frame and the other part of each pump being connected to and movable with said combustion unit, the relative cylinder capacity of said pumps being selectively proportioned to the predetermined desired relative proportions of fuel and oxidizer agent in the combustion mixture but all of said pumps having the same stroke, supply and delivery connections to said pumps, and a check valve in each pump part opening toward said combustion chamber.

ESTHER C. GODDARD,
*Executrix of the Last Will and Testament of
Robert H. Goddard, Deceased.*
